UNITED STATES PATENT OFFICE.

ROGER L. TREWICK, OF SAN FRANCISCO, CALIFORNIA; ROGER TREWICK SPECIAL ADMINISTRATOR OF SAID ROGER L. TREWICK, DECEASED.

MACHINE FOR MAKING SUGAR WAFERS AND THE LIKE.

967,147.

Specification of Letters Patent. Patented Aug. 9, 1910.

Application filed May 28, 1908. Serial No. 435,444.

To all whom it may concern:

Be it known that I, ROGER L. TREWICK, a citizen of the United States, resident of San Francisco, in the county of San Francisco and State of California, have made a certain new and useful Invention in Machines for Making Sugar Wafers and the Like; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a section on the line 1—1, Fig. 2. Fig. 2 is a section on the line 2—2, Fig. 1. Fig. 3 is a front view of the invention. Fig. 4 is a detail fragmentary sectional view showing the lower burners. Fig. 5 is a detail front view illustrating the means for automatically opening and closing the valve of the feed chute. Fig. 6 is a detail cross section of the feed chute. Fig. 7 is a detail bottom plan view of one of the baking pans.

The invention relates to machines for the manufacture of sugar wafers or the like, and it consists in the novel construction and combinations of parts as hereinafter set forth.

In the accompanying drawings, illustrating the invention, the letter *a*, designates an oven inclosure of sheet metal having asbestos lining *b*, to prevent undue escape of heat, said oven having an upper segmental recess of substantially the same length as the diameter of the oven.

c, is a base lying within such inclosure and upon which a rotary circular table *d*, rests, through centrally located ball bearings *d'*, such table having anti-friction roller supports *e*, at the circumference or outer portion thereof, said rollers having movement and bearing upon a circular track *f*, supported from the base *c*. This table has a segmental portion thereof lying without the oven in the segmental recess thereof.

g, *g*, represents a radially arranged series of baking pans which have small securing screws *g'*, uniting the pans to the table *d*, a number of such screws, usually 16, being provided, as shown. These pans *g*, *g*, have each hinged covers *g*², *g*², carrying at their free ends rollers *h*, one roller being provided for each cover, said rollers normally engag-

ing an arcuate track *i*, located above the same within the segmental oven recess and serving to keep the covers tightly closed during the cooking of the pan contents.

The oven inclosure *a*, is of cylindrical form, having an arched cover *a'*, and a straight or vertical front wall *a*², of chord character extending from said cover *a'*, down to the rotary table *d*. In this way the upper portion of the oven lying above the rotary table is provided with a cylinder wall *j*, extending through an arc of about 210 degrees, an arched cover, and a vertical front wall. In order to raise the covers *g*², *g*², of the baking pans when it is desired to remove the contents thereof and recharge the same, the rollers *h*, *h*, of such covers, as they emerge with the pans through the vertical front wall *a*², (which is suitably cut away for this purpose as shown in Fig. 3 of the drawings) pass upon a cam track *k*, whereby the hinged covers are gradually lifted to an angle of about 60 degrees and closed again before the baking pans reenter the inclosure.

Automatically operating means are provided for feeding the dough to the pans, such means consisting in a feed chute or spout *l*, the mouth *l'*, of which is controlled by a plate valve *m*, having extensions *m'*, upon opposite sides of its pivot *m*². This pivot rod *m*², is provided at one end with a four branched wheel *n*, the branches *n'*, of which are adapted to engage pins *o*, *o'*, of the baking pans, each pan having two pins. In this way as the baking pan approaches the wheel *n*, the first pin *o*, strikes a branch *n'*, of the wheel and turns the same, together with the attached valve, through an arc of ninety degrees, whereby the valve is opened, as shown in full lines in Fig. 6. As the pan is about to pass to the other side of the wheel *n*, the pin *o'*, is caused to strike another arm of the wheel *n*, whereby such wheel and the valve is turned again to the same extent, closing the valve as shown in dotted lines in said figure. The contracted mouth *l'*, of the chute or spout *l*, is provided with a slide valve *p*, below the valve *m*, whereby the speed of the discharge of the dough may be controlled.

q, is a horizontal power shaft having bevel gear connection *q'*, with a vertical shaft *q*², which is keyed to the rotary table *d*.

r, is a damper in ventilating pipe *r'*, ex-

tending upward from the center of the arched cover of the oven.

5 *s*, are radial braces for the oven walls located above the rotary table and from which the track *i*, is suspended.

In order to accomplish the cooking of the wafers and to heat the oven I have shown a gas pipe *t*, having parallel branches *t'*, located below the baking pans, said parallel 10 branches having upward projecting burners *t²*, located in close proximity to the pans and below the same, whereby the flames from said burners are caused to strike directly upon the bottoms of the pans as they move 15 past such burners. A similar heating device *u*, is located above the baking pans at a point in the oven beyond the heating device first referred to, its downward projecting burners *u'*, being arranged in close proximity 20 to the closed hinged covers of the pans, whereby the tops as well as the bottoms of the wafers will be perfectly cooked.

A simple and efficient machine for the purpose is thus provided, only one attendant 25 being required, whose duty it will be to remove the wafers from the baking pans as the covers thereof are raised.

Having described the invention, what I claim and desire to secure by Letters Patent 30 is:

1. In a machine of the class described, the combination of a cylindric oven having an upper recess of substantially the same 35 length as that of the diameter of the oven, a rotary table within said oven and having a portion thereof lying without the oven in said recess, a radially arranged series of baking pans upon said table, said pans having each a hinged cover provided with an end 40 roller, a cam track located within the said recess of the oven and with which the end rollers of the pan covers have engagement to raise and lower the same upon movement of the table.

45 2. In a machine of the class described, the combination of a cylindric oven having an upper recess, a rotary table within said oven and having a portion thereof lying without the oven in said recess, a radially arranged 50 series of baking pans upon said table, said pans having each a hinged cover, a cam track located within the recess of the oven and with which the end rollers of the pan covers have engagement to raise and lower the same upon movement of the table, and an arcuate track within the oven and with which the end rollers of the pan covers have engagement to keep said covers closed.

3. In a machine of the class described, the combination of a cylindric oven having an 60 upper recess, a rotary table within said oven and having a portion thereof lying without the oven in said recess, a circular track, supporting rollers carried by the circumferential portion of said table and traveling 65 upon said track, a radially arranged series of baking pans upon said table, said pans having each a hinged cover, a cam track located within the recess of the oven and with which the end rollers of the pan covers 70 have engagement to raise and lower the same upon movement of the table, an arcuate track located within the oven and with which the end rollers of the pan covers have engagement to keep said covers closed, and a 75 feed spout for dough located in said oven recess over the table.

4. In a machine of the class described, the combination of an oven, a rotary table, baking pans carried by said table, and a feed 80 spout for dough having a valve provided with a star wheel, said baking pans having each pins having engagement with said star wheel to automatically open and close said valve.

85 5. In a machine of the class described, the combination of an oven, a rotary table having a small portion thereof located without the oven, baking pans carried by said table, and adapted to pass with said table without 90 the oven, a feed spout for dough located without the oven over said table and having a valve provided with a star wheel, said baking pans having each pins having engagement with said star wheel to automatically 95 control said valve.

6. In a machine of the class described, the combination of an oven, a rotary table having a small portion thereof located without the oven, baking pans carried by said table 100 and adapted to pass with said table without the oven, a feed spout for dough located without the oven over said table and having a valve provided with a star wheel, said baking 105 pans having each pins having engagement with said star wheel to automatically control said valve, said spout having a slide valve for controlling the speed of the dough discharge.

In testimony whereof I affix my signature, 110 in presence of two witnesses.

ROGER L. TREWICK.
